UNITED STATES PATENT OFFICE.

BYRON BENJAMIN GOLDSMITH, OF NEW YORK, N. Y.

DESIGN FOR A LEAD-PENCIL.

SPECIFICATION forming part of Design No. 22,513, dated June 6, 1893.

Application filed February 17, 1893. Serial No. 462,778. Term of patent 14 years.

To all whom it may concern:

Be it known that I, BYRON BENJAMIN GOLDSMITH, a citizen of the United States, and a resident of New York, in the county and State 5 of New York, have invented and produced a new and original Design for Lead-Pencils, of which the following is a specification.

Figure 1, represents a cross-section, and Fig. 2, a perspective view of a lead pencil showing 10 my design.

The leading feature of my design consists in the star-shaped mantle of the lead-pencil, that is to say, the cross-section of the lead-pencil has the shape of a star of the conventional form, with alternating salient and re-entering angles formed by intersecting straight lines.

In the drawings the salient angles 1, 1, 1, &c., are shown as formed by the intersection 20 of the sides 2, 2, &c., of the re-entering angles 3, 3, &c., all uniformly spaced and shaped, so that the cross-section of the mantle may be

looked upon as a regular polygon, the sides of which, instead of being straight, are formed with re-entering angles; these will generally 25 be obtuse angles, while the salient angles will always be acute angles and thereby produce upon the observer the impression of a conventional star. In the center of the star mantle is the lead or graphite 4, which has thus 30 symmetrically grouped about it the inclined flat faces 2', 2', 2', by which the aesthetic effect aimed at is produced.

What I claim is—

The design for a lead pencil, substantially 35 as herein shown and described.

In testimony whereof I have signed my name to this specification in the presence of two subscribing witnesses.

BYRON BENJAMIN GOLDSMITH.
